UNITED STATES PATENT OFFICE.

ROY A. McCOURRY, OF KNAPPA, OREGON.

OVERHEAD CONVEYER.

Application filed June 29, 1926. Serial No. 119,501.

My invention relates to improvements in overhead conveyers, of that type which is commonly used in logging operations, and which includes a carriage movable on an inclined overhead cable or "sky-line" and means for suspending a heavy object, such as a log, from the carriage during the movement of the carriage along the inclined cable line.

- 10 An object of the invention is to improve overhead conveyers of the type referred to by providing on the carriage means for cooperating with the object suspension means of the conveyer to releasably support the object that is to be carried at a given distance below the carriage even though the lines which control the position of the carriage on the carriage supporting line are slack.
- 15 Another object of the invention is the provision in an overhead conveyer of the character described of holding means for releasably maintaining an object that is to be carried at a given distance below the carriage and operable from the ground as the result of a pull on the suspension means to release the suspension means from the holding means so that the object that is being carried may be lowered to the ground
- 20 at any desirable point along the carriage supporting cable.
- 25
- 30

Other objects and advantages of the invention may be apparent from the following description, considered in conjunction with the accompanying drawings, in which—

- 35 Figure 1 is a perspective view of an overhead conveyer equipped with the invention, Figure 2 is a relatively enlarged longitudinal vertical section through a carriage that
- 40 is used in the conveyer, showing the suspension cable holding means that the invention provides in elevation and in position to cooperate with the suspension cable to hold an object that is to be carried at a given dis-
- 45 tance below the carriage,

Figure 3 is a view similar to Figure 2, showing the suspension cable holding means in position to permit movement of the suspension cable as required to lower the object that is to be carried to the ground,

Figure 4 is a perspective group view of the members of an actuating device that is used in the holding means that the invention provides,

50 Figure 5 is a perspective view of the members of a coupling for connecting the adja-

cent ends of sections of a suspension cable that may be used in the aforesaid conveyer, and

Figure 6 is a fragmentary section substantially along the line 6—6 of Figure 2. 60

An overhead conveyer with which the invention may be used is partially shown in Figure 1. This overhead conveyer includes an inclined cable track or "sky-line" 1, the upper end portion of which is suitably connected with the upper end of a mast 2, which is suitably stayed, as by means of the guy lines 3. The complete cable 1 is not shown in the drawings, but it will be understood that the cable 1 extends a considerable distance from the mast 2 and that the lower end of the cable is fixed against movement by suitable means (not shown) so that the cable 1 will be kept taut at all times. A carriage that is adapted to move on the cable 1 may

70 have a frame which includes a pair of fixedly spaced side plates 4 and a pair of peripherally grooved wheels 5 are rotatably supported between the upper portions of the side plates 4, as by means of the transverse shafts 6 which extend between the side plates 4. The respective wheels 5 are in alignment with each other edgewise and rest on the cable 1, the bottoms of the grooves in the peripheries of the wheels 5 being in

75 contact with the cable 1, whereby the carriage will be supported by the cable 1 and is adapted to move along the cable 1. A hold-back line 7 is connected at one end, as at 8, with the side plates 4 of the carriage

80 frame. The hold-back line is passed over the sheave of a pulley 9 which is supported on the mast 2. The hold-back line 7 then is passed through suitably located guide pulleys, as at 10 and 11, respectively, on the

85 ground to a winding and unwinding engine, not shown. The means for suspending an article or load that is to be carried by the carriage from the carriage includes a suspension or hauling cable 12 which in practice 90 extends from a winding engine, not shown, that is located adjacent to the lower end of the cable 1, over a supporting sheave 13 that is supported, as by means of the transverse shaft 14, between the lower portions of 95 the side plates 4 of the carriage frame.

100 The free end of the hauling or suspension cable 12 is adapted to be attached to an object or load, such as the log 15. The parts which have been described so far are ordinary in construction and may vary considerably in details from those which are shown

in the drawings. With the construction that has been described so far, the load or log 15 is hoisted from the ground toward the carriage by a pull on the hauling cable 12 while the hold back cable 7 is kept taut and it is obvious that with the construction that has been described so far, both the hold-back cable 7 and the hauling cable 12 must be kept taut at all times, after the load 15 has been lifted to a desirable height from the ground to prevent the load from dropping downward until the slack has been taken up in the hauling cable. Consequently, care must be taken with the construction that has been described so far to wind up the hauling cable 12 at the same rate at which the hold-back cable has been unwound to permit movement of the carriage on the cable 1 to-ward the lower end of the cable 1. The invention provides means on the carriage and operable by a pull on the cable 12 to engage with an enlarged portion 16 of the cable 12 to prevent retrograde movement of the cable 12 through the carriage should slack occur in the line 12 after the load has been hoisted to a desirable distance below the carriage and operable by a second pull on the cable 12 to release the enlarged portion of the cable 12 so that retrograde movement of the cable 12 through the carriage to effect lowering of the load is permitted.

In carrying out the invention, I provide a guide sheave 17 which is supported between the lower portions of the side plates 4 of the carriage frame, as by means of the transverse shaft 18, in edgewise alignment with the supporting sheave 13 and so that the cable 12 will pass over the guide sheave 17 before engaging with the supporting sheave 13, both the guide sheave 17 and the supporting sheave 13 being peripherally grooved for engagement with the cable 12 so that the portion of the cable 12 that passes through the carriage between the side plates 4 of the carriage will be held against lateral movement. The aforesaid enlarged portion of the cable 12 may be a conventional coupling or union between adjacent ends of sections of the cable 12 and said union may comprise the male coupling member 16^a, the female coupling member 16^b and the set screw 18, the male and female members of the coupling being in threaded engagement with each other and being further connected by the set screw 18, as is usual. A holding or latching wheel 20 is rotatably supported on the transverse shaft 21 between the side plates 4 of the carriage frame directly above and adjacent to the supporting sheave 13 and also in edgewise alignment with the supporting sheave 13. The holding wheel 20 has a plurality of regularly spaced integral outwardly extending radial projections 22 on its periphery. The extremity of each of the

projections 22 is adapted to lie in the groove in the periphery of the supporting sheave 13 as best seen in Figure 6 when the wheel 20 has been turned about its axis so that that projection 22 depends straight downward from the wheel 20 toward the periphery of the supporting sheave 13 and each projection 22 is formed with a longitudinally extending groove or notch 23 in its outer end for cooperating with a relatively deep middle portion 24 of the peripheral groove of the supporting sheave 13 to produce an opening between the periphery of the supporting sheave 13 and the adjacent projection 22 that is substantially circular in cross section and is of slightly greater cross sectional area than the cable 12 proper but of less cross sectional area than the enlarged portion 16 of the cable 12. The holding pawl 25 is supported pivotally adjacent to its upper end between the side plates 4 of the carriage frame by means of a transverse pin 26 so that the lower end portion of the holding pawl bears against the periphery of the wheel 20 and is adapted to engage with the adjacent projection 22 on the wheel 20 to prevent rotation of the wheel 20 in a clockwise direction from the position shown in Figure 2. An expansion spring 27 is connected at one end to a suitable bracket 28 on one of the side plates 4 and bears at its other end against the holding pawl 25 and thus tends to prevent the free end portion of the holding pawl from swinging radially outward beyond the outer end of an adjacent projection 22. A ratchet wheel 29 is axially aligned with the wheel 20 and rigid with the wheel 20, preferably being formed integrally with the wheel 20. The ratchet wheel 29 has regularly spaced teeth 30 on its periphery, there being twice as many teeth 30 as projections 22 on the wheel 20. Each of the teeth 30 includes a relatively long inclined wall 30^a and a shorter radial wall 30^b. An actuating pawl 31 is disposed at the upper side or edge of the ratchet wheel 29 and has a shoulder 32 on its under side adjacent to the free end of the actuating pawl 31 adapted to abut the radial wall 30^b of the adjacent tooth 30 and cause rotation of the ratchet wheel 29 and therefore of the wheel 20 when the actuating pawl 31 is moved longitudinally against the radial wall of the adjacent tooth 30. The actuating pawl 31 is supported at the upper end of a lever 33, being connected with the lever 33 by a pivot element 34 which is parallel with the shaft 21. The lever 33 is fulcrumed intermediate its length on a transverse pin 35 between the side plates 4 and at the side of the ratchet wheel 29 substantially opposite the stop pawl 25. The lower end portion of the lever 33 is enlarged laterally and is bifurcated for a considerable distance from its lower end by the

slot 36, thus producing the furcations or forks 33^a which straddle the cable 12. The fork 36 is sufficiently wide to permit not only the main portion of the cable 12 but the enlarged portion 16 thereof as well to pass through the slot 36. A stop plate 37 has a pair of ears 37^a at its upper end arranged to straddle a pair of outstanding ears 38 on the lower end portion of the lever 33 above the slot 36, the ears 37^a being connected with the ears 38 by a transverse pivot pin 39, whereby the plate 37 may swing to and from position to lie flatwise against the adjacent face of the enlarged lower end portion of the lever 33. The forks 33^a of the lever 33 straddle the cable 12 between the guide sheave 17 and the supporting sheave 13 and the plate 37 is disposed at the side of the lever 33 next to the supporting sheave 13. The lower end of the plate 37 terminates substantially flush with the lower end of the lever 33 and the plate 37 is formed with a vertical slot 40 which extends from the lower end of the plate 37 for approximately the same height as the slot 36. The slot 40 is sufficiently wide to permit the main portion of the cable 12 to pass therethrough but is of less width than the diameter of the enlarged portion 16 of the cable 12. An expansion spring 41 has one end attached to a suitable bracket 42 on the inner face of one of the side plates 4 and bears at its other end against the outer face of the lever 33 at the level of the pin 35 on which the lever 33 is fulcrumed, whereby the spring 41 will function to maintain the lever 33 normally in vertical position.

From the foregoing description of the various parts of the device, the operation thereof will be readily understood. Swinging of the lower end of the lever 33 from the position shown in Figure 3 to the position shown in Figure 2 or in other words in the general direction of the guide sheave 17 will actuate the pawl 31 to turn the ratchet wheel 29 and consequently the holding wheel 20 through a part of a revolution, the periphery of the holding wheel moving under the stop pawl 25. The return movement of the actuating pawl 31 from the position shown in Figure 2 to the position shown in Figure 3 will not actuate the ratchet wheel 29 as the pawl 31 will ride along an inclined wall of one of the teeth 30 and will not engage with a radial wall 30^b of a tooth 30. The teeth 30 on the ratchet wheel are arranged relatively to the projections 22 on the holding wheel so that two successive operating strokes of the actuating pawl 31 are required to turn the holding wheel 20 through one third of a complete revolution, there being three of the projections 22 on the holding wheel or in other words through a part of a revolution equal to the distance on the

periphery of the holding wheel 20 from the center of one of the projections 22 to the center of the adjacent projection 22. Therefore, when the holding wheel 20 is in such position that one of the projections 22 is disposed vertically at the lower edge of the holding wheel 20 and extends into the peripheral groove at the upper edge of the supporting sheave 13 as shown in Figures 2 and 6, one operating stroke of the actuating pawl 31 will turn the holding wheel so that the edge portion of the holding wheel that is located directly above the vertical diametrical line of the supporting sheave 13 will be located midway between the adjacent projections 22 and the peripheral groove in the upper edge portion of the supporting sheave 13 will be entirely unobstructed so that both the main portion of the cable 12 and the enlarged portion 16 of the cable 12 may pass freely along the peripheral groove in the upper edge portion of the supporting sheave 13. A second operating stroke of the pawl 31 will turn the holding wheel 20 until one of the projections 22 depends into the peripheral groove in the upper edge portion of the supporting sheave 13 and then the enlarged portion 16 of the cable 12 cannot pass along the peripheral groove in the upper edge portion of the supporting sheave 13 between the bottom of said peripheral groove and the adjacent projection 22, only the main portion of the cable 12 being permitted to pass between the end of the adjacent projection 22 and the bottom of the peripheral groove in the upper edge portion of the supporting sheave 13. The holding pawl 25 will prevent return rotary movement of the holding wheel 20 after the holding wheel has been turned to any possible position by means of the actuating pawl 31 and the ratchet wheel 29. The position of the holding wheel when one of the projections 22 depends into the peripheral groove in the upper edge portion of the supporting sheave 13 and cooperates with the latter to prevent passage of the enlarged portion 16 of the cable between the projection 22 and the periphery of the supporting sheave 13 may be termed the active or latching position of the holding wheel 20 and the position of the holding wheel 20 when a portion of its periphery between adjacent projections 22 is located directly above the vertical median or diametrical line of the supporting sheave 13 and the peripheral groove in the upper edge portion of the supporting sheave 13 is unobstructed may be termed the inactive or non-latching position of the holding wheel 20.

In the operation of the device, the free end of the cable 12 is attached to the load 15 that is to be carried while the holding wheel 20 is in inactive or non-latching position as shown in Figure 3. The cable 12

then is drawn over the supporting sheave 13 and the guide sheave 17 and through the slots 40-36 of the members 37 and 33, which are located between the supporting sheave 13 and the guide sheave 17, until the enlarged portion 16 of the cable 12 contacts with the plate 37 at the side edges of the slot 40, at which time the load 15 will have been hoisted until it is well above the ground and is at a desirable distance below the carriage. A slight further pull on the cable 12 will cause the plate 37 and the lever 33 to be swung as a unit from the position shown in Figure 3 to the position shown in Figure 2, whereby the actuating pawl 31 will be actuated to effect turning of the ratchet wheel 29 and the holding wheel 20 until the holding wheel 20 is in active or latching position with respect to the supporting sheave 13. The cable 12 then may be slackened slightly to permit the enlarged portion 16 thereof to move backward against the lower end of the adjacent projection 22 and the periphery of the upper edge portion of the supporting sheave 13, after which further retrograde movement of the portion of the cable 12 on which the load 15 is suspended will be prevented so long as the holding wheel 20 is in active or latching position, no matter how much slack may occur in the remaining portion of the cable 12. The spring 41 will function to return the lever 33 and the plate 37 from the position shown in Fig. 2 to the position shown in Figure 3 as soon as the pressure of the enlarged portion of the cable 12 on the plate 37 has been removed. Therefore, when it is desired to lower the load 15 to the ground from said given distance below the carriage, it only is necessary to pull the cable 12 forward until the enlarged portion 16 thereof has again engaged the plate 37 and has actuated the plate 37 and the lever 33 to effect through the agency of the actuating pawl 31 and the ratchet wheel 29 rotation of the holding wheel 20 from active or latching position as shown in Figure 2 to inactive or non-latching position as shown in Figure 3. Since the slot 36 in the lower end portion of the lever 33 is wider than the diameter of the enlarged portion 16 of the cable 12 and the plate 37 is hingedly attached to the lever 33 to swing away from the lower end portion of the lever 33 toward the holding wheel 20, it is obvious that the entire cable 12, including the enlarged portion 16 thereof may be drawn back over the guide sheave 17 and over the supporting sheave 13 when the holding wheel 20 is in inactive or non-latching position, if such retrograde movement of the cable 12 should be desired at any time.

The device is simple in construction and reliable in use and when applied to the carriage of a conveyer of the type shown in

the drawings will effect an economy in the time and labor that will be required for the transportation of a given load for a given distance along the carriage supporting cable or "sky-line".

70

Obviously, the invention is susceptible of embodiment in forms other than that illustrated in the accompanying drawings, and I therefore consider as my own all such modifications and adaptations thereof as fairly fall within the scope of the appended claims.

75

I claim:

1. In a conveyer, a cable having an end portion attachable to a load that is to be carried and having an enlarged portion adjacent to said attaching end portion, a movable overhead supporting sheave over which said cable is trained, a rotary holding wheel disposed in edgewise alignment with said supporting sheave and adjacent to said supporting sheave, said holding wheel having a plurality of regularly spaced projections on its periphery, each of said projections being adapted when in a position proximate to the periphery of said supporting sheave to cooperate with said supporting sheave to prevent passage of the enlarged portion of said cable between said projections and the periphery of said supporting sheave, and means for actuating said holding wheel to dispose said projections successively in or out of position proximate to the periphery of said supporting sheave.

80

85

90

95

2. In a conveyer, a cable having an end portion attachable to a load that is to be carried and having an enlarged portion adjacent to said attaching end portion, a movable overhead supporting sheave over which said cable is trained, a rotary holding wheel disposed in edgewise alignment with said supporting sheave and adjacent to said supporting sheave, said holding wheel having a plurality of regularly spaced projections on its periphery, each of said projections being adapted when in a position proximate to the periphery of said supporting sheave to cooperate with said supporting sheave to prevent passage of the enlarged portion of said cable between said projections and the periphery of said supporting sheave, and means for actuating said holding wheel to dispose said projections successively in or out of position proximate to the periphery of said supporting sheave, means for preventing return rotary movement of said holding wheel, said holding wheel actuating means being adapted to be actuated by said enlarged portion of the cable.

100

105

110

115

120

3. In a conveyer, a cable having an end portion attachable to a load that is to be carried and having an enlarged portion adjacent to said attaching end portion, a movable overhead supporting sheave over which said cable is trained, a rotary holding wheel disposed in edgewise alignment with said

125

130

- supporting sheave and adjacent to said supporting sheave, said holding wheel having a plurality of regularly spaced projections on its periphery, each of said projections being 5 adapted when in a position proximate to the periphery of said supporting sheave to cooperate with said supporting sheave to prevent passage of the enlarged portion of said cable between said projections and the periphery of said supporting sheave, means for 10 actuating said holding wheel to dispose said projections successively in or out of position proximate to the periphery of said supporting sheave, each of said projections on the holding wheel and the periphery of said supporting sheave having cooperative 15 grooves for the passage of the main portion of the cable and constituting a way of less cross sectional area than the cross sectional area of said enlarged portion of the cable. 20
4. In a conveyer, an overhead carriage including a pair of spaced side plates, a supporting sheave disposed between said side plates, a holding wheel disposed between said side plates above said supporting sheave, said holding wheel having regularly spaced 25 projections on its periphery adapted to be moved successively when said holding wheel is turned about its axis to positions to extend close to the periphery of said supporting sheave, a cable having an end portion attachable to a load that is to be carried and having an enlarged portion adjacent to said attaching portion, said cable being passed over said supporting sheave, said supporting sheave having a peripheral groove and each of said projections on the holding wheel having a groove in its outer end adapted to cooperate with the groove in the periphery of the holding wheel when said projection is proximate to said periphery of the supporting sheave to produce a way in which the main portion of said cable may move longitudinally, said way being of less area 30 in cross section than said enlarged portion of the cable, means operable by the enlarged portion of said cable to turn said holding wheel a part of a revolution equal to half the distance on the periphery of the holding wheel between the centers of adjacent projections on the holding wheel, means for preventing return rotary movement of said holding wheel after said holding wheel has been turned in one direction by said actuating means, and a 35 guide sheave supported between said side plates substantially at the level of said supporting sheave and in edgewise alignment with said supporting sheave, said cable passing over said guide sheave, said holding wheel actuating means comprising a ratchet wheel rigid with the holding wheel and in axial alignment with the holding wheel, said ratchet wheel having twice as many teeth 40 on its periphery as there are projections on said holding wheel, an actuating pawl engageable with the teeth of the ratchet wheel successively to effect turning of said ratchet wheel and said holding wheel in said one direction about the axial line of the holding wheel, and a lever operable by said enlarged portion of the cable for actuating said actuating pawl. 45
5. In a conveyer, an overhead carriage including a pair of spaced side plates, a supporting sheave disposed between said side plates, a holding wheel disposed between said side plates above said supporting sheave, said holding wheel having regularly spaced 50 projections on its periphery adapted to be moved successively when said holding wheel is turned about its axis to positions to extend close to the periphery of said supporting sheave, a cable having an end portion attachable to a load that is to be carried and having an enlarged portion adjacent to said attaching portion, said cable being passed over said supporting sheave, said supporting sheave having a peripheral groove and each of said projections 55 on the holding wheel having a groove in its outer end adapted to cooperate with the groove in the periphery of the supporting sheave when said projection is proximate to said periphery of the supporting sheave. 60
6. In a conveyer, an overhead carriage including a pair of spaced side plates, a supporting sheave disposed between said side plates, a holding wheel disposed between said side plates above said supporting sheave, said holding wheel having regularly spaced 65 projections on its periphery adapted to be moved successively when said holding wheel is turned about its axis to positions to extend close to the periphery of said supporting sheave, a cable having an end portion attachable to a load that is to be carried and having an enlarged portion adjacent to said attaching portion, said cable being passed over said supporting sheave, said supporting sheave having a peripheral groove and each of said projections 70 on the holding wheel having a groove in its outer end adapted to cooperate with the groove in the periphery of the supporting sheave when said projection is proximate to said periphery of the supporting sheave. 75
7. In a conveyer, an overhead carriage including a pair of spaced side plates, a supporting sheave disposed between said side plates, a holding wheel disposed between said side plates above said supporting sheave, said holding wheel having regularly spaced 80 projections on its periphery adapted to be moved successively when said holding wheel is turned about its axis to positions to extend close to the periphery of said supporting sheave, a cable having an end portion attachable to a load that is to be carried and having an enlarged portion adjacent to said attaching portion, said cable being passed over said supporting sheave, said supporting sheave having a peripheral groove and each of said projections on the holding wheel having a groove in its outer end adapted to cooperate with the groove in the periphery of the supporting sheave when said projection is proximate to said periphery of the supporting sheave. 85
8. In a conveyer, an overhead carriage including a pair of spaced side plates, a supporting sheave disposed between said side plates, a holding wheel disposed between said side plates above said supporting sheave, said holding wheel having regularly spaced 90 projections on its periphery adapted to be moved successively when said holding wheel is turned about its axis to positions to extend close to the periphery of said supporting sheave, a cable having an end portion attachable to a load that is to be carried and having an enlarged portion adjacent to said attaching portion, said cable being passed over said supporting sheave, said supporting sheave having a peripheral groove and each of said projections on the holding wheel having a groove in its outer end adapted to cooperate with the groove in the periphery of the supporting sheave when said projection is proximate to said periphery of the supporting sheave. 95
9. In a conveyer, an overhead carriage including a pair of spaced side plates, a supporting sheave disposed between said side plates, a holding wheel disposed between said side plates above said supporting sheave, said holding wheel having regularly spaced 100 projections on its periphery adapted to be moved successively when said holding wheel is turned about its axis to positions to extend close to the periphery of said supporting sheave, a cable having an end portion attachable to a load that is to be carried and having an enlarged portion adjacent to said attaching portion, said cable being passed over said supporting sheave, said supporting sheave having a peripheral groove and each of said projections on the holding wheel having a groove in its outer end adapted to cooperate with the groove in the periphery of the supporting sheave when said projection is proximate to said periphery of the supporting sheave. 105
10. In a conveyer, an overhead carriage including a pair of spaced side plates, a supporting sheave disposed between said side plates, a holding wheel disposed between said side plates above said supporting sheave, said holding wheel having regularly spaced 110 projections on its periphery adapted to be moved successively when said holding wheel is turned about its axis to positions to extend close to the periphery of said supporting sheave, a cable having an end portion attachable to a load that is to be carried and having an enlarged portion adjacent to said attaching portion, said cable being passed over said supporting sheave, said supporting sheave having a peripheral groove and each of said projections on the holding wheel having a groove in its outer end adapted to cooperate with the groove in the periphery of the supporting sheave when said projection is proximate to said periphery of the supporting sheave. 115
11. In a conveyer, an overhead carriage including a pair of spaced side plates, a supporting sheave disposed between said side plates, a holding wheel disposed between said side plates above said supporting sheave, said holding wheel having regularly spaced 120 projections on its periphery adapted to be moved successively when said holding wheel is turned about its axis to positions to extend close to the periphery of said supporting sheave, a cable having an end portion attachable to a load that is to be carried and having an enlarged portion adjacent to said attaching portion, said cable being passed over said supporting sheave, said supporting sheave having a peripheral groove and each of said projections on the holding wheel having a groove in its outer end adapted to cooperate with the groove in the periphery of the supporting sheave when said projection is proximate to said periphery of the supporting sheave. 125
12. In a conveyer, an overhead carriage including a pair of spaced side plates, a supporting sheave disposed between said side plates, a holding wheel disposed between said side plates above said supporting sheave, said holding wheel having regularly spaced 130 projections on its periphery adapted to be moved successively when said holding wheel is turned about its axis to positions to extend close to the periphery of said supporting sheave, a cable having an end portion attachable to a load that is to be carried and having an enlarged portion adjacent to said attaching portion, said cable being passed over said supporting sheave, said supporting sheave having a peripheral groove and each of said projections on the holding wheel having a groove in its outer end adapted to cooperate with the groove in the periphery of the supporting sheave when said projection is proximate to said periphery of the supporting sheave. 130

to produce a way in which the main portion of said cable may move longitudinally, said way being of less area in cross section than said enlarged portion of the cable, 5 means operable by the enlarged portion of said cable to turn said holding wheel a part of a revolution equal to half the distance on the periphery of the holding wheel between the centers of adjacent projections on the holding wheel, means for preventing return rotary movement of said holding wheel after said holding wheel has been turned in one direction by said actuating means, a guide sheave supported between said side plates substantially at the level of said supporting sheave and in edgewise alignment with said supporting sheave, said cable passing over said guide sheave, said holding wheel actuating means comprising a ratchet wheel 10 rigid with the holding wheel and in axial alignment with the holding wheel, said ratchet wheel having twice as many teeth on its periphery as there are projections on said holding wheel, an actuating pawl engageable with the teeth of the ratchet wheel successively to effect turning of said ratchet wheel and said holding wheel in said one direction about the axial line of the holding wheel, a lever operable by said enlarged portion 15 of the cable for actuating said actuating pawl, said lever being pivotally connected at its upper end with said actuating pawl and being fulcrumed intermediate its length between said side plates of the carriage, the lower end portion of said lever having a vertical slot through which said cable, including the enlarged portion thereof is passed, and a plate hinged to the lower end portion of said lever at the side of the latter next to said holding wheel and having a slot through which the main portion of said cable may pass but of insufficient width to permit the passage of the enlarged portion 20 of the cable therethrough.

45 7. In a conveyor, a carriage including a pair of spaced side plates, a supporting sheave disposed between the side plates, a guide sheave disposed between said side plates in edgewise alignment with said supporting sheave and substantially at the same level as said supporting sheave, a holding wheel rotatively supported between said side plates above said supporting sheave and having projections regularly spaced on its periphery and adapted when the holding wheel 30 is turned to be disposed successively in proximity to the upper portion of the periphery of said supporting sheave, a cable passed

over said supporting sheave and then over said guide sheave and between said supporting sheave and said holding wheel, said cable having an enlarged portion and each of said projections on the holding wheel and said supporting sheave having grooves co-operating to produce a way of greater cross sectional area than the main portion of said cable and of less cross sectional area than said enlarged portion of the cable, a ratchet wheel rigid with said holding wheel and in axial alignment with the holding wheel, said ratchet wheel having twice as many teeth on its periphery as there are projections on said holding wheel, an actuating pawl engageable with the teeth of the ratchet wheel successively to cause intermittent rotary movement of said ratchet wheel and of said holding wheel, two successive operating strokes of said actuating pawl being required to turn said holding wheel a part of a complete revolution equal to the distance from the periphery of the holding wheel between the centers of adjacent projections on said holding wheel, a lever fulcrumed intermediate its length between said side plates above the space between said supporting sheave 45 and said guide sheave, the upper end portion of said lever being pivotally connected with said actuating pawl and the lower end portion of said lever having a slot adapted to straddle said cable when said lever is in vertical position and the actuating pawl is at the end of its return stroke after actuating said ratchet wheel, said slot in the lower end portion of said lever being wider than the enlarged portion of said cable, and a supporting plate hingedly attached to the lower end portion of said lever at the side of the latter next to said ratchet wheel, said plate having a vertical slot substantially in register with the slot in the lower end portion 50 of the lever, the slot in said plate being wider than the main portion of said cable but of less width than the enlarged portion of said cable, a spring acting on said lever to tend to maintain said lever in vertical position and the actuating pawl therefor at the end of its return stroke, and a spring-pressed pivoted pawl engageable with the periphery of the holding wheel and with the projections thereon to prevent return rotary movement of the holding wheel after said holding wheel has been turned in one direction through the agency of said actuating pawl.

ROY A. McCOURRY.
